UNITED STATES PATENT OFFICE

WILLIAM E. HANN, OF DETROIT, MICHIGAN

DESIGN FOR A RADIATOR FRONT

Application filed November 4, 1930. Serial No. 37,532. Term of patent 14 years.

To all whom it may concern:

Be it known that I, WILLIAM E. HANN, a citizen of the United States, residing at Detroit, in the county of Wayne and State of Michigan, have invented a new, original, and ornamental Design for Radiator Front, of which the following is a specification, reference being had to the accompanying drawing, forming part thereof.

Fig. 1 is a view in side elevation of an automobile radiator front embodying the improved design.

Fig. 2 is a view of the front elevation of the same.

Fig. 3 is a fragmentary view in perspective of the upper portion of same.

Fig. 4 is a sectional view taken along line 4—4 of Fig. 1 looking in the direction indicated.

What I claim is:

The ornamental design for a radiator front as shown.

WILLIAM E. HANN.
